[57] CLAIM

The ornamental design for an ergonomic stethoscope chestpiece, as shown and described.

DESCRIPTION

FIG. 1 is a top plan view of an ergonomic stethoscope chestpiece, showing our new design;

FIG. 2 is an enlarged top plan view thereof;

FIG. 3 is a bottom plan view thereof;

FIG. 4 is a side elevational view thereof; the opposite side elevational view being identical thereto;

FIG. 5 is a front elevational view thereof; and,

FIG. 6 is a rear elevational view thereof.

The broken line showing in FIGS. 1-3 is for illustrative purposes only and forms no part of the claimed design.

FIG. 1

FIG. 2

FIG. 3
